2,248,453

ENGINE GOVERNOR

Ralph M. Fingar, Painted Post, and Charles Taylor, Corning, N. Y., assignors to Ingersoll-Rand Company, Jersey City, N. J., a corporation of New Jersey

Application September 30, 1939, Serial No. 297,204

4 Claims. (Cl. 123—140)

The present invention relates to an engine over-speed safety stop and, more particularly, it relates to a device associated with an engine which stops the operation of the engine when it reaches excessive speeds.

In an oil engine particularly of the Diesel type employed to operate an air compressor, it is very essential that the engine be prevented from overspeeding with possible detrimental results to both the engine and the apparatus being driven.

Accordingly, it is an object of the present invention to provide a device which will prevent the engine from running at excessive speeds.

Another object is to provide an engine over-speed safety stop which is simple in construction and operates efficiently.

Still another object is to provide an engine over-speed safety stop which may be operated automatically or manually.

A still further object is to provide an engine over-speed safety stop which may be used in conjunction with a standard engine governor.

These and further objects will be apparent from the following description and drawings. In the drawings, similar numerals refer to similar parts.

Figure 1 is an elevational view of a portion of an oil engine incorporating the present invention.

Figure 2 is a view partly in section and partly in elevation of a fuel pump as shown in Fig. 1.

Figure 3 is a view in section taken along line 3—3 of Fig. 1.

Figure 4 is a sectional view taken along line 4—4 of Fig. 3.

The engine, generally indicated at 1, comprises one or more cylinders 3 mounted above the crankcase 5. The cylinders 3 exhaust to a common exhaust manifold 7 and each cylinder is provided with a fuel pump 9. As shown in Fig. 2, the fuel pumps 9 are operated by appropriate cams 11 mounted on the cam shaft 13 which is shown dotted in in Fig. 1.

The fuel pumps 9 will not be described in detail since they form no part of the present invention and are of the standard construction of the type wherein a reciprocating plunger serves to pump the fuel. The plunger is so arranged that the fuel may be by-passed from the pump to the storage space and the amount of fuel so by-passed may be regulated by rotation of the plunger.

As will be seen in Fig. 1, the pumps 9 are mounted on a base 15 which is itself mounted on the engine frame. The base 15, as shown in Fig. 2, is provided with a port 17 over which the pump

9 is mounted. In the lower part of the base is a second port or passage 19 to receive the bushing 21. The push-rod 23, having a roller 25 to engage the cam 11, extends through the bushing 21 and is adapted to reciprocate in the bushing in accordance with the movement of the cam 11. The shoulder 27 extends beyond the outer surface of the push-rod 23 and is adapted to bear against the end of the bushing 21 and the base 15.

10 The upper end of the push-rod is designed to contact the pump plunger 29 and to cause it to reciprocate in order to force fuel into the cylinders. Fuel is supplied to the pump through the header 31 and to the cylinder from the pump by conduit 33. As is well known, the means of rotating the pump plunger, in order to control the amount of fuel by-passed, is a rack 35. To the outer end of the rack is attached the eye 37 which pivotally connects with the rack. The eye 37 is designed to be connected to the fuel control rod 39 which is actuated by the governor 41.

Since the governor is of standard construction, the details thereof will not be described. The governor is mounted on the engine in a casing 43. The end of the camshaft 13 extends within this casing and has keyed thereto a gear 45. This gear may be employed to drive the governor and also to drive the device of the present invention. Extending from one wall of the casing 43 is a stationary shaft 47 on which is mounted a gear 49 and a disk 51. The disk 51 has a passage 53 extending diametrically therethrough and through which extends the rod 55. At one end of the rod the recess 57 is formed in the disk to communicate with the passage 53 and to receive the spring 59 which is maintained therein by the washer 61 mounted on the end of the rod 55. The other end of the rod 55 carries the weight 63 and normally rests on a flattened portion 65 of the disk 51. During ordinary operation of the engine the camshaft will rotate, thus causing the gear 45 to rotate the gear 49.

Unless the speed becomes excessive, the weight 63 will rest on the disk 51 under the influence of spring 59. Upon an increase in speed beyond a predetermined maximum, which is determined by the adjustment of the tension of spring 59, the centrifugal force set up upon rotation of the gear 49 will cause the weight 63 to compress the spring 59 and to move outwardly away from the disk. Directly above the gear 49 is a lock or trigger 67 secured on the pivot 69, which is fastened on the casing 43. The trigger 67 has two arms 71 and 73. The arm 71, being designed to contact the weight 63 when this weight is thrown to its

outwardmost position by an excessive speed. The other arm 73 has a shoulder 75 to engage the shoulder 71 on the head 79 which forms a part of the plunger 81.

The plunger extends through the governor casing 43 and is provided with a button 83 at a point outside of the casing. The transverse wall 85 of the casing 43 has a recess 87 in which rests the cup 89. Resting on the inside bottom wall of the cup is the spring 91 which surrounds the plunger 81. Another cup 93, which is inverted with respect to the cup 89 and slidably therein, is suitably secured to the plunger 81 by the pin 95 and is designed to maintain the spring in cup 89 under compression when the plunger 81 is in its lowermost position. The plunger may be held in this position by the arm 73 of the trigger engaging the head 79 of the plunger.

To one side of the trigger is a manual push button 97 adapted to slide within the wall 99 which projects beyond the casing wall 43. The push button 97 has a small spindle 101 surrounded by the spring 103. The spring 103 tends to push the button 97 away from the casing wall but is prevented from so doing by the ring 105. From this it is apparent that, when the push button 97 is pushed to compress the spring 103, the spindle 101 will strike the arm 73 of the trigger 67. In this manner it is possible to push the trigger out of its restraining position and to permit the plunger 81 to rise under the influence of spring 91. Likewise, the weight 63 may strike the trigger arm 71 and allow the plunger 81 to rise.

As will be seen in Fig. 4, a lever 107 surrounds the plunger 91 and is secured to the fuel control shaft 39 by a key 109. The governor controls the speed of the engine by the movement of the fuel control rod 39 and is, accordingly, directly connected to this rod. For this reason, the lever 111 is also secured to the rod 39. This lever has two horizontal arms 113 and 115. At the outer end of each arm is an adjusting screw 117 provided with appropriate lock nuts. Below each adjusting screw is a stop 119 to limit the movement of the screws 117 and their respective arms. A tie-rod 121 is pivoted on a pin 123 provided on the arm 125 of lever 111. The other end of the tie-rod extends through the pivot 127 mounted on the lever 129 which is directly connected to and movable by the governor. Between the shoulder 131, formed on the tie-rod 121 and the pivot 127, a spring is placed and the tension of this spring may be controlled by the nuts 132.

If, for instance, the engine should speed up, the lever 129 would then move to the right, thereby moving arm 125 of lever 111 toward the right. If the governor should be decreasing the speed of the engine, the said screw 117 on the arm 113 would strike its respective stop 119 and thus stop further decrease in speed by the governor. Under such conditions, it appears that lever 107, surrounding the plunger 91, may rock in accordance with the lever 111, since they are both connected to the fuel control rod 39. In the event that the speed of the engine should exceed the speed for which the governor is set, the weight 63 will move outwardly and strike arm 71 of the trigger 67 thus releasing the plunger 81. Under the influence of the spring, the plunger will rise

and the cup 93 will strike the lever 107 thus raising it until the adjusting screw 117 on arm 115 of lever 111 strikes its respective stop 119. The length of the adjusting screw 117 is so adjusted that when it strikes its stop 119, the fuel rod will move the racks 35 for each of the fuel pumps 9 to such a position that all of the fuel entering through the header 31 will be by-passed and, since no fuel will flow to the cylinders 3, the engine will stop.

We claim:

1. In an engine, the combination of an engine speed governor, a fuel pump for each engine cylinder, a rack for each pump, a control shaft connected to the racks movable by the governor to regulate the amount of fuel supplied to the engine, a plunger, a lever on the control shaft movable by the plunger, a spring normally urging the plunger to move the lever and control shaft and render the fuel pumps inoperative, a latch to normally hold the plunger against movement by the spring, a rotor driven by the engine, a weight on the rotor, and a spring to normally restrain the weight adapted to compress as the weight moves out due to centrifugal force to strike the latch when the speed of the engine becomes excessive.

2. In a multicylinder engine, the combination of an engine speed governor, fuel supply means for each cylinder, means actuated by the governor to regulate the quantity of fuel supplied to each cylinder by the fuel supply means, movable means to urge the regulating means to render the fuel supply means inoperative to supply fuel to the engine, means to normally restrain the last means, means rotated by the engine, and means on the rotatable means to render the restraining means ineffective when the engine speed exceeds a predetermined maximum.

3. In an engine, the combination of an engine speed governor, a fuel pump, a fuel pump control shaft movable by the governor to regulate the amount of fuel supplied to the engine, a plunger, a lever on the fuel pump control shaft movable by the plunger, a spring normally urging the plunger to move the lever and shaft to a position rendering the engine inoperative, a catch on the plunger, a trigger to engage the catch and hold the plunger during operation of the engine, and a resiliently held weight rotated by the engine adapted to strike the trigger and release the plunger at a predetermined speed.

4. In an engine, the combination of an engine speed governor, a fuel pump for each engine cylinder, a control rack for each pump, a control shaft connecting the pump racks movable by the governor to regulate the amount of fuel supplied to the engine, a plunger, a lever on the control shaft movable by the plunger, means normally urging the plunger to move the lever and control shaft to a position to prevent the supply of fuel from the fuel pumps to the engine, restraining means to normally prevent movement of the plunger, means rotated by the engine, and means on the last means to render the restraining means ineffective at a predetermined engine speed.

5. In an engine, the combination of an engine speed governor, a fuel pump for each engine cylinder, a control rack for each pump, a control shaft connecting the pump racks movable by the governor to regulate the amount of fuel supplied to the engine, a plunger, a lever on the control shaft movable by the plunger, means normally urging the plunger to move the lever and control shaft to a position to prevent the supply of fuel from the fuel pumps to the engine, restraining means to normally prevent movement of the plunger, means rotated by the engine, and means on the last means to render the restraining means ineffective at a predetermined engine speed.
